MINIATURE WALL SHELF

Noah Rubin, New York, N. Y., assignor to National Plastic Corp., New York, N. Y., a corporation of New York

Application February 25, 1950, Serial No. 8,142

Term of patent 3½ years

(Cl. D33—3)

To all whom it may concern:

Be it known that I, Noah Rubin, a citizen of the United States, residing in New York city, county, and State of New York, have invented a new, original, and ornamental Design for Miniature Wall Shelf, of which the following is a specification, reference being had to the accompanying drawing, forming a part thereof, in which:

Fig. 1 is a front elevational view of my new design for a miniature wall shelf;

Fig. 2 is a side elevational view thereof, and
Fig. 3 is a top plan view thereof.

The opposite side is similar to that shown in Fig. 2.

I claim:

The ornamental design for a miniature wall shelf, as shown and described.

NOAH RUBIN.
